[57] CLAIM

The ornamental design for a lollipop holder, as shown and described.

DESCRIPTION

FIG. 1 is a front elevational view of a lollipop holder, showing my new design;

FIG. 2 is a left-hand end view thereof;

FIG. 3 is a right-hand view thereof;

FIG. 4 is a top plan view thereof; and,

FIG. 5 is a bottom plan view thereof. The appearance of the rear is a mirror image of the front shown in FIG. 1. The dashed lines in FIG. 1 show the intended use of the article to hold lollipops but are not a part of the design.
